UNITED STATES PATENT OFFICE.

GEORGE M. PARSONS, OF OHIO, ILLINOIS.

END-GATE FOR WAGONS.

No. 863,432.

Specification of Letters Patent.

Patented Aug. 13, 1907.

Application filed April 3, 1907. Serial No. 366,187.

To all whom it may concern:

Be it known that I, GEORGE M. PARSONS, a citizen of the United States, residing at Ohio, in the county of Bureau and State of Illinois, have invented new and useful Improvements in End-Gates for Wagons, of which the following is a specification.

This invention relates to an end gate for farm wagons and the like of that type which is firmly locked in position so that danger of the gate jolting open or out and 10 the spilling of the contents of the wagon is positively prevented.

The invention has for one of its objects to improve and simplify the construction and operation of devices of this character so as to be comparatively easy and inexpensive to manufacture, readily manipulated, and thoroughly effective in use.

A further object of the invention is the provision of a tail or end gate having hingedly connected sections that are adapted to be folded and unfolded in placing and 20 removing the gate, an automatic lock being employed for holding the sections of the gate in position.

Another object of the invention is the provision of an end gate composed of a plurality of parts slidably mounted in guideways on the sides of the wagon body, 25 the lower part being composed of sections so arranged as to be readily placed or removed without changing the position of the other part or parts of the gate.

With these objects in view and others, as will appear as the description proceeds, the invention comprises 30 the various novel features of construction and arrangement of parts which will be more fully described hereinafter and set forth with particularity in the claims appended hereto.

In the accompanying drawing, which illustrates one 35 of the embodiments of the invention, Figure 1 is an end view of the tail gate of a wagon. Fig. 2 is a longitudinal section on line 2—2, Fig. 1. Fig. 3 is a vertical transverse section on line 3—3, Fig. 1.

Similar reference characters are employed to designate 40 corresponding parts throughout the several views.

Referring to the drawing, A designates a wagon body of ordinary construction comprising a bottom 1, sides 2 and spaced members 3 on the inner surfaces of the sides to form guideways for receiving the ends of the gate 45 members that are slidable vertically into and out of position in the usual manner, a tightening rod 4 passing through the sides of the body being employed for holding the parts of the gate clamped in position.

In the present instance, the gate is composed of two 50 members 5 and 5', the latter resting on the bottom 1 of the body and the former being held in position by the clamping of the sides of the body tightly against the ends of the member so that the lower member of the gate can be moved without the top member sliding 55 down. The lower member is composed of two sections

6 and 7 hingedly connected by ordinary hinges 8 applied to the inner surfaces of the sections, as clearly shown in Fig. 2. This permits the meeting ends of the sections to be drawn outwardly so as to remove the bottom member of the gate when it is desired to dump the 60 grain at the elevator or other material that is contained in the wagon.

The sections are of unequal length and secured to the rear surface of the shorter section is a plate 9 that overlaps to a considerable extent the longer section. 65 This plate has a longitudinal slot 10 over which extends a latch member 11 that is hinged at its inner end to the member 12 which is screwed or otherwise suitably secured to the plate 9, the latch member being so mounted as to swing rearwardly during the unlocking of the 70 member. The latch member is held in closed position by a leaf spring 13 that is anchored under the hinge plate 12, as shown by dotted lines at 14 and secured to the latch member 11 by extending under a staple 15 on the inner face of the member. Extending into the 75 slot from the section 6 and latch member 11 is an interlocking staple 16 and hook 17, whereby the latch member prevents the sections of the gate from swinging open. Adjacent the hook 17 is a curved leaf spring 18 that serves as a guide for directing the staple 16 into 80 engagement with the hook 17. The free end of the latch member is engaged between the fingers and swung outwardly, thereby releasing the staple 16 and hook 17, the staple 16 passing outwardly between the spring 18 and free extremity of the hook 17. In order 85 to facilitate the gripping of the latch member, the plate 9 is notched at 19 so that the finger can be engaged under the latch member. When the latch member is swung outwardly, the spring 13 is flexed, as shown by dotted lines, Fig. 2, and by pulling outwardly on 90 the latch member, the gate member can be withdrawn, the sections thereof swinging to the dotted line position during this operation. In returning the gate member, the outer ends of the sections thereof are adjusted to the guideways formed by the members 3 and then 95 by applying an inward pressure to the sections, they will assume the full line position shown in Fig. 2. During this movement of the gate sections, the staple 16 strikes the spring 18 and causes the latter to disengage from the hook 17 and also guides the hook 16 100 into interlocking position. In addition to the function of guiding the staple 16 into locking position, the spring 18 serves as a stop against which the free end of the hook 17 bears, as shown by dotted lines, Fig. 2, to hold the latch member in open position, and when the 105 spring is disengaged from the hook by coming into contact with the staple 16, the latch member will immediately swing closed by the spring 13 so that the hook and staple will interlock.

It will thus be seen that the section of the gate mem- 110

ber 5 can be readily manipulated for placing or removing the gate member and the parts are normally held automatically in closed position.

From the foregoing description taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired, as are within the scope of the claims.

Having thus described the invention, what I claim is:—

1. The combination of a wagon body with an end gate, said gate comprising a member composed of hingedly connected sections, a plate on one of the sections, a spring actuated latch member therein, and an interlocking hook and staple on the latch member and the other section of the gate.
2. An end gate comprising hingedly connected sections, a member fixedly secured to one section and overlapping the other, a spring-actuated latch on the member, an interlocking hook and staple on the latch member and adjacent section of the gate.

3. An end gate comprising hingedly connected sections, a plate fixed on one of the sections and overlapping the other and provided with a slot, a hinged latch member, a spring for holding the latter in normal position, and fixed interlocking devices disposed in the slot of the plate and fixed on the latch member and adjacent section of the gate.

4. An end gate comprising hingedly connected sections, a plate secured to one of the sections and overlapping the other, a hinged latch member, an interlocking hook and staple on the latch member and adjacent gate section, and a resilient member attached to the plate and serving as a stop for holding the latch member in open position.

5. An end gate comprising hingedly connected sections, a slotted plate secured to one of the sections and overlapping the other, a hinged latch member disposed on the slot, a leaf spring secured to the plate and latch member for holding the latter in normal position, an interlocking hook and staple disposed in the slot and rigidly secured to the latch member and adjacent gate section, and a spring secured to the plate and arranged in co-operative relation with the hook and staple for assisting in engaging the latter and co-operating with the hook to serve as a stop for holding the latch member open.

In testimony whereof, I affix my signature in presence of two witnesses.

GEORGE M. PARSONS.
